UNITED STATES PATENT OFFICE

HENRI EMIL WITZ, OF OBERHAUSEN, GERMANY, ASSIGNOR TO THE BABCOCK & WILCOX COMPANY, OF BAYONNE, NEW JERSEY, A CORPORATION OF NEW JERSEY

MECHANICAL STOKER FOR FORCED-DRAFT FURNACES

Application filed June 21, 1923, Serial No. 646,735, and in Germany August 3, 1922.

This invention relates to improvements in and connected with mechanical stokers for forced draft furnaces, and is an improvement in or modification of the invention described in the specification of the application of Johannes Bronold, Serial No. 628,364, filed March 28, 1923, Patent No. 1,480,988.

As is pointed out in said prior application it is of advantage effectively to seal certain exposed parts of the furnace and stoker structure when operating with forced draft and to provide means for withdrawing and leading away dust and furnace gases which would otherwise contaminate the atmosphere of the boiler room. The dust and furnace gas, are, of course, liable to escape, due to the fact that in a forced draft furnace the combustion chamber is under a slightly greater pressure than atmospheric.

20 The present invention, while producing the same effect, permits of avoiding the closing in of the front of the grate, so that the grate is accessible from the front and the grate tract can be supervised.

25 Two embodiments of the invention are illustrated in the accompanying drawing, in which Fig. 1 is a vertical, longitudinal section of one embodiment. Fig. 2 is a similar view of a modification. Fig. 3 is a section 30 showing some of the details of another modification.

Referring to Fig. 1 of the drawing, 1 is the combustion chamber, 2 the fuel hopper, 3 the upper run of the grate, which is shown 35 somewhat diagrammatically in the drawings, 4 a sealing box arranged between the upper and lower runs, and 5 a sealing plate arranged under the lower run, which, together with the box 4, completely seals the rear part of the 40 grate from the front. 6 is a shutter or gate regulating the height of the fuel layer. Between the shutter 6 and the rear wall of the hopper 2 is provided a hollow space 7, which is connected by means of a duct 8 with the 45 inlet side of a fan, with the chimney or with a boiler pass. The hollow space 7 is so constructed that the partial vacuum produced exerts its suction action both above the shutter 6 and also at the side thereof, so that, at 50 this point, flue gases emerging from the fur-

nace are immediately drawn off and cannot therefore pass into the boiler house.

The suction action is further increased by providing a sealing off plate 9 at the front end of the grate beneath the upper run of the 55 grate, permitting less air to pass from the boiler house into the hollow space 7.

Referring to Fig. 2, slots 11 are provided in the box 4', these slots extending the width of the box. The dust, which is forced forward through the grate interstices, owing to the forced draft pressure in the rear part of the grate, therefore passes through the openings 11 into the box 4' and from there, through piping 12 connected to the box, to a dust 60 separator arranged in the basement, where it is separated out. Care need only be taken that the sealing surfaces in front of the opening 11, between which surfaces the grate passes, are selected of such length that the resistance 65 opposed in this part to the passage of the air is greater than the resistance inside the box 4', the piping 12 and the separator 13. The separator may be of the usual "cyclone" construction in which the air leaves the separator 70 through the pipe 120 while the dust after having been removed owing to the whirling action imparted to the air and dust mixture is withdrawn at 130. The separator is not 75 absolutely necessary and the box may itself be 80 constructed as a separator by means of suitable baffles therein, as shown by the box 4'' in Fig. 3. In this construction, fuel riddling through from the upper run of the stoker may be removed through the opening 140 of 85 box 4'', while the dust entering through the opening 11' from the lower run is removed 90 through opening 110 and thus the fuel riddling through the upper run of the stoker may be recovered free from the dust from 95 other parts of the furnace.

By means of an opening 14 or 14' provided in and passing through the upper side of the box 4' or 4'' respectively, the smoke-suction action on the lower run of the grate can also 95 be increased. The openings 110 and 140, can, if necessary, be connected to the chimney or to another suction device.

I claim:—

1. In combination, a forced draft furnace 100

having a chain grate stoker, means for supplying forced draft to the rear part of the stoker, a fuel gate to regulate the thickness of coal on said stoker, a hopper spaced from said fuel gate and in front of the same, means for placing the region between the gate and hopper and above said stoker under sub-atmospheric pressure, a member sealing the upper and lower runs of the stoker at the forward end thereof, and means for removing dust through said sealing means.

5 2. In combination, a forced draft furnace having a chain grate stoker, means for supplying forced draft to the rear part of the
15 stoker, a member sealing the upper and lower runs of the stoker at the forward end thereof, said member having an aperture opposite a run of the stoker, and means for creating a draft from said stoker through
20 said aperture whereby dust is drawn from the stoker into said member.

25 3. In combination, a forced draft furnace having a chain grate stoker, means for supplying forced draft to the rear part of the stoker, a member sealing the upper and lower runs of the stoker at the forward end thereof, said member having an aperture opposite a run of the stoker, means for creating a draft from said stoker through said
30 aperture whereby dust and gas is drawn from the stoker into said member, a conduit connected therewith, and a dust separator in said conduit.

35 4. In a forced draft furnace, a chain grate stoker, a sealing device for said stoker comprising a box-like member located between the runs of the grate, said member having sealing surfaces for the upper and lower runs of the grate at the forward end thereof, said
40 member being provided with an aperture in a sealing surface, a baffle in said member in the path of gases passing through said aperture, and means for creating a draft through said aperture from said grate.

45 5. In a forced draft furnace, a chain grate stoker, a sealing device for said stoker comprising a box-like member located between the runs of the grate, said member having sealing surfaces for the upper and lower runs of the grate, said member being provided with an aperture in its upper and an aperture in its lower sealing surfaces, baffles in said member arranged so as to separate dust passing through from the upper run independently
50 of the dust from the lower run, and means for creating a draft through said aperture from said grate.

HENRI EMIL WITZ.
